UNITED STATES PATENT OFFICE.

WARREN JACOB GEIB, OF MADISON, WISCONSIN.

DESIGN FOR A CAMPAIGN BADGE, BUTTON, OR BANNER.

49,089.

Specification for Design.

Patented May 23, 1916.

Application filed January 18, 1916. Serial No. 72,862. Term of patent 7 years.

To all whom it may concern:

Be it known that I, WARREN JACOB GEIB, a citizen of the United States, residing at Madison, in the county of Dane and State of Wisconsin, have invented a new, original, and ornamental Design for a Campaign Badge, Button, or Banner, of which the following is a specification, reference being had to the accompanying drawing, forming part thereof.

The figure is a plan view of a badge illustrating my new design.

I claim—

The ornamental design for campaign badge, button, or banner as shown.

WARREN JACOB GEIB.
